(57) **CLAIM**

The ornamental design for a toilet seat with chrome edge, as shown and described.

DESCRIPTION

FIG. 1 is a perspective view of a toilet seat with chrome edge;

FIG. 2 is a top view thereof;

FIG. 3 is top view thereof with a raised cover;

FIG. 4 is a bottom view thereof;

FIG. 5 is a front side view thereof with a raised cover;

FIG. 6 is a front side view thereof; and,

FIG. 7 is a right side view thereof.

The broken lines shown in the drawings represent portions of the toilet seat that form no part of the claimed design.
